(57) **CLAIM**

The design for strapless swim goggles, as shown and described.

DESCRIPTION

FIG. 1 is a front view of the goggles showing the new design;

FIG. 2 is a rear view of the goggles of FIG. 1;

FIG. 3 is a right side view of the goggles of FIG. 1;

FIG. 4 is a left side view of the goggles of FIG. 1;

FIG. 5 is a bottom rear angle view of the goggles of FIG. 1;

FIG. 6 is a bottom rear perspective view of the goggles of FIG. 1;

FIG. 7 is a top rear perspective view of the goggles of FIG. 1;

FIG. 8 is a bottom front perspective view of the goggles of FIG. 1;

FIG. 9 is an alternate bottom rear perspective view of the goggles of FIG. 1;

FIG. 10 is a top front perspective view of the goggles of FIG. 1;

FIG. 11 is a top plan view of the goggles of FIG. 1;

FIG. 12 is a bottom plan view of the goggles of FIG. 1;

FIG. 13 is a bottom front angle view of the goggles of FIG. 1;

FIG. 14 is a front side angle view of the goggles of FIG. 1;

FIG. 15 is an enlarged partial rear side perspective view of the goggles of FIG. 1; and,

FIG. 16 is an alternate bottom rear perspective view of the goggles of FIG. 1.
